LIQUID DISPENSING BRUSH

Berdene R. Fisher, Valley Center, Kans.

Application February 5, 1947, Serial No. 726,661

1 Claim. (Cl. 15—138)

1

My invention relates to an improvement in liquid dispensing brushes and refers more particularly to hair brushes, although the device is applicable to such brushes as paint brushes, scrub brushes and the like.

The object of my invention is to provide a brush having space therein for carrying a supply of liquid such as hair tonic, liquid soap, paint, cleaner liquids of various kinds, etc., that may be dispensed into or among the bristles of the brush in desired quantities from time to time as the brush is being used.

A further object is to provide a brush of the kind mentioned that is comparatively simple in construction, easy to make, and one that is comparatively inexpensive to make and sell. These and other objects will be more fully described as this description progresses.

Now referring to the accompanying drawings in which similar numerals of reference designate the same parts throughout the several figures of the drawings; Fig. 1 is a bottom plan view of the brush, part of the bristles being removed for convenience of illustration.

Fig. 2 is a side view of the brush device.

Fig. 3 is a top plan view of the brush device.

Fig. 4 is a longitudinal detail sectional view through the brush device, the view being taken along the line IV—IV in Fig. 3 and looking in the direction of the arrows.

Fig. 5 is a front end view of the brush device as seen from the line V—V in Fig. 2 and looking in the direction of the arrows.

Fig. 6 is a rear end view of the brush device as seen from the line VI—VI in Fig. 2 and looking in the direction of the arrows.

Fig. 7 is a rear and sectional view of the brush device, the view being taken along the line VII—VII in Fig. 3 and looking in the direction of the arrows.

Fig. 8 is an enlarged detail sectional view of the valve mechanism employed in the brush device shown in the foregoing described figures, the view being taken along the line VIII—VIII in Fig. 4 and looking in the direction of the arrows.

Fig. 9 is an enlarged rear face view of the slide valve plate.

Fig. 10 is an enlarged front end view of the handle portion of the brush device at the point of joinder of the handle to the brush assembly and showing the valve slide groove and liquid passage.

Fig. 11 is a detail sectional view through a modified form of the invention, the view being

2

taken along the line XI—XI in Fig. 12 and looking in the direction of the arrows.

Fig. 12 is a longitudinal and vertical sectional view of the modified form of the invention.

5 In the drawings is shown a brush device having a hollow brush head 15 that has a brush base 16 in which is inset tufts of bristles 17 between which are openings or passages 18 through the brush base 16 and opening into the chamber 19 10 in the brush head 15.

The brush head 15 is provided with a hollow handle element 20, the rear end of which is provided with a removable closure plug 21 that is threaded thereto. The other end of the handle 15 20 is provided with a closure plate 22 that is an integral part of the handle 20, and a segment of an annular flange-like portion 23 and a tongue-like guide element 24 is formed thereon and projecting slightly therebeyond is integrally 20 formed thereon and abuts a like formation on the rear end of the brush head 15 and is permanently and rigidly cemented or welded thereto; this assembly provides a slot-like space 25 in which a valve slide plate 26 is slidably carried.

25 The valve slide plate consists of the plate 26 having an elongated and longitudinally positioned slot 27 therein and in which is positioned the said tongue-like element 24 which functions 30 as a guide and retainer for the plate 26 as will later and further be described. The valve plate 26 is provided with a round valve hole 28 that is adapted to move in and out of registry with a substantially V-shaped hole or opening 29 in the end plate 22 of the handle element 20. The slide valve plate 26 is provided with an operating 35 knob 30 that depends therefrom and projects below the handle 20 and brush base 16 as shown.

Depending from the brush head 15 and extending downwardly therefrom into the chamber 19, and spaced a little in front of the slide valve plate 26 is a plate-like element 31 against which rests a metallic plate 32 that is made of spring material and from which a leaf spring 33 is 40 formed and tensioned to bear against the slide valve plate 26 and hold the plate 26 in position as a closure over the triangular shaped opening 29 in the closure plate 22 of the handle element 20 when the two holes 28 and 29 are out of registry with each other.

45 The operation of the device is as follows: the device is prepared for use by first removing the plug 21 from the handle element 20 and then 50 filling the cavity in the handle element 20 with

the desired liquid, hair tonic, liquid soap, water, or the like, and then replace the plug 21.

Now by pressing on the knob 30, the valve plate 26 may be slipped endways until the valve hole 28 comes either partially or entirely into registry with the V-shaped passage 29, whereupon the liquid in the handle 20 will flow through that portion of the V-shaped passage 29 that is in registry with the valve hole 28, and also through the valve hole 28 into the cavity 19 of the brush head 15 and drain through the brush base passages 18 onto the drain downwardly on the bristles 17, whereupon the user of the brush may brush his or her hair, during which process the liquid will be imparted to the hair as desired. The amount of liquid desired, and the speed with which the liquid may be governed by the size of the opening 28-29, created by the amount of the V-shaped passage 29 brought into registry with the valve hole 28.

In Figures 11 and 12 is shown a modification of the device and in which is shown the brush head 15a, brush base 16a, having bristle tufts 17a therein, and the perforations or liquid passages 18a therein and between the bristle tufts 17a that open into the brush head cavity or chamber 19a the same as described for Figs. 1 to 8 inclusive. Also within the chamber 19a is a slide valve plate 26a that is perforated or provided with a multiplicity of valve openings 28a, one for each passage 18a in the brush base 16a and adapted to be moved in and out of registry with the passages 18a as will later be described. The valve plate 26a fits closely and rests on the brush base 16a and is slidable thereon. The valve plate 26a is held in contact with the brush base 16a by means of a pair of L-shaped guides or retainer elements 25a and 25b that are positioned, one on opposite sides of the brush head 15a and slide valve plate 26a with one leg of each L resting on the slide valve plate 26a and the other leg of each L being rigidly attached, riveted, welded, or cemented, to the adjacent side wall of the brush head 15a. The slide valve plate 26a is provided with an operating arm 26b that is integrally formed on one end thereof and extends upwardly and rearwardly therefrom. The extreme end of the operating arm 26b is turned upwardly and passes through and is operable in a slot 34 in the brush head 15a. The upturned end of the operating arm 26b is provided with a button or knob 30a that fits closely on, and is slidable on the outer face of brush head 15a, and the button 30a covers the entire slot 34 at all times to provide a liquid tight closure for the slot 34.

The brush head 15a is provided with a handle 20a, one end of which is threaded as at 35 into an opening 36 in the rear end of the brush head 15a and opens into the cavity or chamber 19a in the brush head 15a.

This device is prepared for use by first unscrewing and removing the handle 20a from the brush head 15a and then filling the chamber 19a with the desired liquid by pouring the liquid through the opening 36 into the chamber 19a. This having been done, the handle 20a may now be replaced in the brush head 15a in the same manner it was removed and the device is now ready for use.

To use the device, the bottom 30a may be moved to slip the valve plate 26a to a position

where the openings 28a therein come partially or entirely into registry with the passages 18a in the brush base 16a, whereupon the liquid in the chamber 19a will flow through the passages 28a-18a and drain onto and down the tufts of the bristles 17a and will be imparted therefrom onto the hair of the user of the brush as he or she brushes his or her hair.

Such modifications of my invention may be employed as lie within the scope of the appended claims without departing from the spirit and intention of the invention. Now having fully shown and described my invention, what I claim as new and desire to secure by Letters Patent is—

- 15 In a liquid dispensing brush device of the kind described; said device having in combination, a hollow brush head and a hollow brush handle, one side of the brush head being a brush back and having tufts of bristles rigidly fixed therein and projecting therefrom, said brush back having a plurality of liquid passages therethrough and positioned intermediate the tufts of bristles, one end of the brush head having an abutment plate formed thereon to receive one end of the said 20 hollow brush handle, said abutment plate having means therein to permit the passage of a liquid from without the hollow of the brush head to the hollow of the brush handle, one end of the hollow handle having a closure plate made as an integral 25 part thereof, the outer face of the closure plate having a slide valve seat formed therein and having a combination slide valve guide tongue and handle abutment element thereon, said closure plate having a substantially V-shaped opening 30 therethrough, a slide valve plate, said valve plate having a valve opening and an elongated guide slot therein, said valve plate being longitudinally positioned in the said valve seat and having the said guide tongue positioned through the said slot, 35 the said valve plate having an integral and centrally located and depending operating finger piece that projects below the handle element, and spring means engageable against the valve plate to hold the valve plate against the valve seat to 40 form a closure for the V-shaped opening, the handle and guide tongue being engageably fitted against the said brush head abutment plate and permanently affixed thereto, said valve plate being slidable longitudinally to move the valve opening therein into variable degrees of registry with the said V-shaped opening to admit governed amounts of liquid from the hollow of the handle into the hollow of the brush head for dispensation through the openings in the brush back 45 and onto the tufts of bristles, and means on the outer end of said handle for closing the hollow of the handle.

BERDENE R. FISHER.
